UNITED STATES PATENT OFFICE.

LLOYD C. HAYNES, OF LOS ANGELES, CALIFORNIA.

COLLAR-FASTENING CLIP.

1,171,950.

Specification of Letters Patent. Patented Feb. 15, 1916.

Application filed October 23, 1913. Serial No. 796,789.

To all whom it may concern:

Be it known that I, LLOYD C. HAYNES, a citizen of the United States, residing in the city of Los Angeles, Los Angeles county, State of California, have invented a certain new and useful Improvement in Collar-Fastening Clips; and I do hereby declare the following to be a full, clear, and exact description thereof, reference being had to the accompanying drawings, and to the letters of reference marked thereon, which form a part of this specification.

This invention relates to a clip or fastener for securing a collar to a shirt band, and has special reference to the device for securing the collar at the back of the neck.

The objects I have in view are to produce a fastener in which there will be no unpleasant pressure on the neck of the wearer, which will be easily attached, and which may be also utilized for confining the tie or cravat.

The invention is particularly applicable to fasteners used with shirts with a double or two-piece neck band, although the invention is not restricted to such use.

The drawings illustrate an embodiment of the invention, in which—

Figure 1 is a perspective view of the upper part of a shirt band, and standing collar showing a fastening clip embodying my invention, in position, illustrating the position of the collar when subjected to strain incident to applying the front fastener to the right-hand end of the collar; Fig. 2 is a similar view showing the collar fastening in place, and with a tie; Fig. 3 is a perspective view of a preferred form of fastening clip; Fig. 4 is a perspective view on the line 4—4 of Fig. 2; Fig. 5 is a plan view of the device illustrated in Fig. 3; and Fig. 6 is a diagrammatic view on an enlarged scale, showing the clip in position within the pocket between the inner and outer shirt band, and also showing the position of the button hole of the collar when subjected to strains incident to fastening the right-hand end of the collar on the front of the neck band.

In all of the views like parts are indicated by the same reference characters.

In the drawings the following parts of the shirt and collar are indicated by small letters, as follows: *a* is the inside shirt band; *b* is the outside shirt band; *c* is the collar; *d* is the tie; *e* is the pocket formed

between the inner and outer shirt band; *f* is the top of the pocket, the bottom of the pocket being open; *g* is the button hole in the outside shirt band; *h* is the button hole in the collar; and *i* is the front collar fastener.

The improved clip is best shown in Fig. 3, and comprises a body portion 1, and a tongue 2. The tongue extends outwardly and then downwardly, as shown. At its extremity is a hook 3. This hook extends out to one side. In connection with collars in which the right-hand end is first fastened the hook extends to the left, as illustrated. With collars in which the left-hand end is first fastened the hook should extend to the right. The body 1 extends a sufficient distance on each side of the tongue, so that it will partly fill the pocket *e*, and prevent rotation of the body therein when the tongue is subjected to the strain of the collar during the operation of fastening the right-hand end. As the button hole *g*, formed in the shirt band, is some distance below the upper edge *f* of the pocket, I provide that the tongue shall extend off from the body at a point below the upper edge of the body, as shown. This will allow the upper edge of the body to engage with the top of the pocket, so that the clip will not twist within the pocket.

The device is applied as follows: It is introduced through the button hole *g* by first passing the hook 3 and then the tongue 2, through the button hole *g*. The tongue is then introduced through the collar button hole *h*, and the user then fastens the right-hand end of the collar to the front collar button *i*. He is free to use both hands for this purpose, without need of holding the left-hand end of the collar. The considerable strains put upon the clip, due to the fastening of the front of the collar, are resisted by the hook 3, which prevents the collar button hole from slipping off of the tongue. The upwardly extending portion of the body to the right of the tongue will engage with the top *f* of the pocket, hence the clip will not be twisted. This tendency to twist will also be resisted by the stiffness of the material which forms the outside shirt band *b*, and which contains the button hole *g*.

Fig. 6 illustrates diagrammatically the strains in which the parts are subject; the arrow at the bottom illustrates the line of stress caused by the pulling of the collar in

- order to fasten the right-hand front end; the vertical arrow near the top illustrates the stresses upward of the body, which are resisted by the top *f* of the pocket.
- 5 The device can be made in any way, although I prefer to make it out of metal, stamped out of one piece. It can be employed with collars of all types, and may be used or not with the tie *d*, which passes 10 under the tongue.

Having now described my invention, what I claim as new and desire to secure by Letters Patent, is:—

- 15 1. A clip for fastening collars to a shirt band which comprises a laterally extending body portion adapted to lie inside of the shirt band, and within the pocket thereon, and a tongue extending at an angle to the body and then parallel to the body from a 20 point removed from the edge of the body, said tongue being adapted to pass through the button holes of the shirt band and collar, and a hook on one side of the extremity of the tongue said hook being located beyond 25 the edge of the body and adapted to prevent accidental displacement of the collar when one end is being fastened at the front, the

upper edge of the body being adapted to engage with the top of the pocket to prevent rotation of the clip.

30

2. As a new article of manufacture, a collar fastening clip comprising a single piece of sheet metal stamped to shape, a laterally extending body portion adapted to lie inside the neck band of a shirt and within the 35 pocket thereon, an integral tongue extending at an angle from about the middle of the body portion, said tongue then extending parallel to the body and at right angles to the greatest length of the body to a point 40 beyond the edge of the body portion, a hook on the free extremity of the tongue, said hook being located entirely beyond the edge of the body and extending parallel to the body portion and to one side of the tongue, 45 the said hook being adapted to engage the back buttonhole of a collar.

This specification signed and witnessed this twenty-second day of October, 1913.

LLOYD C. HAYNES.
